UNITED STATES PATENT OFFICE.

GEORGES KLEEFELD, OF BRUSSELS, BELGIUM.

SEARCHLIGHT.

1,414,985.

Specification of Letters Patent. Patented May 2, 1922.

Application filed December 9, 1921. Serial No. 521,267.

To all whom it may concern:

Be it known that I, GEORGES KLEEFELD, a subject of the King of the Belgians, residing at 53 Rue du Congrès, Brussels, Belgium, 5 have invented certain new and useful Improvements in Searchlights (for which I have made application in Belgium, November 26, 1920, and Germany Dec. 8, 1920,) of which the following is a specification.

10 The present invention has for its object improvements in searchlights, and particularly in searchlights for motor cars.

It has been found that when a motor car is running at high speed and more especially when it follows an irregular path, the driver experiences much difficulty in perceiving distant objects and curves in the road and especially curves with a small radius, on account of the fact that the zone of lighting

20 obtained by ordinary searchlights is coaxial with the car, whilst the direction to be taken is generally at a more or less extended angle to the same.

It has been found also that the maximum 25 zone of lighting is desirable when the vehicle is traversing certain non-congested roadways whereas during travel through congested districts it is necessary to reduce the glare of the lights, diffused light being 30 preferably used.

In a general way, two lighting systems are available, the first for obtaining a strongly lighted zone at a relatively long range, and the second for obtaining a dim or diffused 35 light for driving in towns or other districts where traffic is congested.

According to the present invention, an apparatus has been provided which, whilst affording ample illumination laterally of the 40 vehicle, will permit either of an intense lighting at long range, or of a reduced lighting with diffused light.

The arrangement of the invention comprises:

45 1°. A lighting source, which is preferably, although not essentially, an electric lamp.

50 2°. A reflector producing a main strong lighting zone, coaxial with the vehicle, and of two intense secondary lighting zones, situated one on each side of the main lighting zone, and at a suitable distance from the same. For this purpose, the invention comprises the combination of a main paraboloid, 55 and of two sections of secondary paraboloids,

the axes of which are set at an appropriate angle to the axis of the main paraboloid.

3°. An arrangement for varying the position of the lighting source with respect to the reflector.

4°. Means by which the gaps between the main lighting zone and the secondary lighting zones can be eliminated, and to this effect, the generating curve of the secondary surfaces of reflection can be a complex curve 65 composed of juxtaposed parts of paraboloids having appropriate parameters, projecting rays, received from the lighting source in adjacent sectors, connecting the main part of the lateral light bundles with the main 70 light bundle.

The invention is shown, by way of example, in the accompanying drawings, in which—

Fig. 1 is a central horizontal section of 75 a searchlight;

Fig. 2 is a view similar to Fig. 1, showing the means for connecting the lateral light bundles with the main light bundle;

Fig. 3 is a vertical section of the whole 80 arrangement.

Referring to the drawing in detail, the reflector comprises a main paraboloid X the axis of which is directed according to A—A. and the focus of which is at F.

85 In order to obtain secondary lighting zones, the main paraboloid with focus F is combined with two secondary paraboloids y^1 and y^2 having respectively foci F' and F'' , the axes of which coincide with lines 90 B B and C C. As seen, the meeting point K of AA, BB and CC is situated in front of the different foci, at a distance which will practically be such that if a lighting source is brought to point K, the light rays 95 reflected by the surfaces of the main paraboloid and the portions of secondary paraboloids y^1 and y^2 are concentrated in points of the axes AA, BB and CC which are situated at such distances from point K and 100 from each other that even in the case of a curve with a small radius, the internal, as well as the external side of the curve are completely lighted. Practically, the centers of the secondary light zones can be situated 105 at about 40 meters in front of point K, and at a distance of 15 to 20 meters from the axis AA.

In the arrangement shown in Fig. 3, 1 is the lighting source which, in the present 110

case, is a glow lamp, mounted in a socket 2 slidable in an opening provided in the reflector 3. The socket is connected by means of an internally flanged ring 5, with a sleeve 4 which latter is threaded for axial adjustment in a threaded sleeve 6 mounted in the casing 7 of the searchlight. As seen, the socket 2 is normally urged towards its extreme forward position by a spring 9 engaged at one end with the sleeve 4 and at its opposite end with ring 5, the sleeve 4 having a stop flange 10 engaging the front of the internal flange of the ring 5.

The arrangement comprises also means 15 for pulling the socket 2 rearwardly, said means being, in the case shown, a cable 11 fixed at one end at 12 to the socket 2 and at the other end to a hand lever 14^a mounted on a bracket 14 attachable to the driving 20 wheel column, (not shown) and a flexible sheath 13 surrounding cable 11 and received at one end in a recess 15 of sleeve 4 and at the other end in a similar recess 16 in the bracket 14.

25 The previous adjustment of the position of the lighting source is obtained by rotation in a suitable sense, of the screw member 6 abutting against the external casing 7 of the search light. The rotation of the sleeve 30 6 effects the longitudinal displacement of the sockets 4 and 2 along the axis of the searchlight. The sheath of the cable 11, though flexible, is non-twistable and, being forcibly inserted in the inside of the socket 35 4, prevents said socket from rotating with the sleeve 6. It is obvious that in the case of several similar searchlights mounted on the same vehicle, the actuating cables 11 for the different sockets can all be connected with 40 the same lever 14^a, and the simultaneous displacements of the different lighting sources obtained by a single movement of the handle. It is also understood that in the same case, a separate adjustment of the positions of the 45 various lighting sources is necessary, which may be easily obtained by a suitable manipulation of the adjusting sleeve 6. As previously stated, when the lighting source lies at K, the principal and secondary lighting zones are obtained. When the car 50 travels through a town or a village, the lighting source is brought back by a suitable movement of the handle, to the position indicated by M (axis A—A) in Fig. 1.

55 In this case, the main paraboloid will reflect the rays in a diverging manner and the secondary paraboloids will act only weakly, with the result that a lighting of very reduced intensity and diffused light will be 60 obtained.

In order to connect the bundle of rays projected by the main paraboloid with those projected by the secondary surfaces of reflection y^1 and y^2 , as previously explained 65 and shown in Fig. 2, the sizes and param-

eters of the paraboloid sections can easily be determined according to the desired light distribution, but a preferred solution consists in providing secondary surfaces, of which for instance 40% (part A¹ B¹ of the 70 generating curve having its axis A'—A') are reserved to the formation of the lighted zones which are angularly most distant, and are spreading into bundles having proportionally the most important openings, whilst 75 the neighbouring 30% (part B¹ C¹ of the generating curve having the axis B'—B') are made of a paraboloid section of smaller parameter and the axis of which is less inclined on the main axis, whereby the formed 80 lighting zones spread into bundles of less opening, and so on, the reflecting sections C' to D', D' to E' and E' to F' having the axes C'—C', D'—D' and A—A, respectively. 85

In the distribution of light by this type of reflector, the most intense lighting zones are the central zone of the main bundle and the extreme lateral zones of the secondary bundles, and, between the latter and the main 90 bundle, zones of decreasing lighting intensity from the said extreme lateral secondary zones to the principal bundle.

It is clear that reverse effects can also be obtained, i. e., zones of decreasing intensity 95 from the main zone, by reversing the above described arrangement.

It is also clear that, by multiplying the 100 number of parabolic sections constituting the generating curve of the secondary surfaces y^1 and y^2 , and reaching the limit, secondary surfaces will be obtained giving a uniform lighting in all points of the secondary bundles and connected with the main bundle. 105

Having now described my invention, I hereby declare that what I claim is:

1. A headlight for motor vehicles and the like, comprising a lighting source and a reflector having a main paraboloid of revolution and two secondary reflecting surfaces, arranged laterally on either side of the main paraboloid and extending on either side of the main horizontal symmetrical plane of the reflector, the secondary reflecting surfaces being composed of paraboloid sections the axes of which are disposed at angles to the axis of the main paraboloid, and at an angle to each other, the axis of the main paraboloid and the axes of the paraboloid 115 sections being situated within the main symmetrical horizontal plane of the reflector. 115

2. In a headlight, a lighting source and a reflector having a main paraboloid section projecting a main strong lighting zone and two secondary reflecting sections arranged laterally on either side of the main paraboloid section and projecting intense lighting zones on each side of the main lighting zone, the secondary reflecting sections being 125 130

composed of complex paraboloid curves the axes of which are disposed at varying angles to the axis of the main paraboloid section and at angles to each other, the complex 5 curvature of the secondary paraboloid sections causing the projection of light over the areas between the main strong lighting zone and the intense lighting zones.

3. A headlight for motor vehicles and the 10 like comprising a lighting source, a casing, a reflector, means for permanently regulating, according to the horizontal axis of the reflector, the position of the lighting source, said means consisting in the combination of 15 a slideable lamp socket and screw-threaded connected sleeves, one of said sleeves being

in engagement with said socket and the other sleeve abutting against the casing of the headlight, and means, independent of the first named means, for temporarily 20 modifying the position of the lighting source along the main horizontal axis of the reflector, said means comprising a telescopic connection of the lamp socket and the socket engaging sleeve, and an elastic member nor- 25 mally maintaining the lamp socket in forwardly projected position.

In testimony whereof I affix my signature.
GEORGES KLEEFELD.
